UNITED STATES PATENT OFFICE.

HARRY H. HONIGBAUM, OF RICHMOND HILL, NEW YORK.

SHINGLE.

Application filed October 20, 1923. Serial No. 669,712.

This invention relates to shingles and while the construction is adapted especially to be incorporated in composition shingles, the shingle of this invention may be made 5 of any material and may be constructed as an individual shingle or as a strip shingle or in the running yard.

The object of the invention is to provide a simple and economical shingle construction 10 which will simulate the old conventional wooden shingles when laid upon a roof. Most of the composition shingles, as now constructed, when laid upon a roof lay so flat as to produce a blank or flat appearance 15 since the shingles do not stand out in sufficiently bold relief to give the aesthetic appearance so pleasing in wood shingled roofs.

The shingle of this invention is so constructed that the shingle elements will stand 20 out in bold relief and thus obviate the flat appearance referred to.

In one of the practical embodiments of the invention, it is constructed in strip form, the strip being slit transversely at intervals for 25 a portion of its width and at the base of each transverse slit a relatively short longitudinal slit is formed. The edges of each transverse slit are thereupon turned under to provide transverse openings extending 30 from the weather edge of the shingle strip for an appreciable portion of the width of the strip, so that when such shingle strips are laid in successive courses, the portions between the successive slits of each course 35 will simulate wooden shingles while the turned in edges of the slits will cause the shingle portions to stand out in bold relief from the shingle elements of the subjacent course and overcome the flat appearance.

Roofing may be made in the running yard in 40 this manner and individual shingles may also be constructed in the same way except that instead of slitting the shingles transversely short slits parallel to the weather 45 edge are required in the lateral edge of each individual shingle in order that a portion of each lateral edge may be turned under. This turning under operation is accomplished during the process of manufacture 50 and in the case of composition shingles and while the material is in a warm and plastic condition so that when the material cools the turned under portions will maintain their positions.

Features of the invention, other than those specified, will be apparent from the hereinin-

after detailed description and claim, when read in conjunction with the accompanying drawings.

The accompanying drawings illustrate 60 one practical embodiment of the invention, but the construction therein shown is to be understood as illustrative, only, and not as defining the limits of the invention.

Figure 1 shows a blank and illustrates the 65 cuts necessary to produce the strip shingle shown in Figure 2;

Figure 2 shows a completed strip shingle made in accordance with this invention; and, 70

Figure 3 shows a modified construction. 75

In making a strip shingle in accordance with this invention, a blank 1 of appropriate width and length is slit transversely by slits 2 which extend from the weather edge 3 an appreciable distance toward the top edge of the strip and abut short longitudinal slits 4 which extend longitudinally of the strips a short distance either side of each slit 2. The ends of the strip are also provided with short longitudinal slits 5 substantially equal in 80 length to one half the length of the slits 4. After the blank has been slit in the manner described the marginal edges of the slits 2 are folded under or returned upon themselves to form in effect reinforcing flanges 6, the short slits 4 permitting such folding without tearing or disruption of the blank. At the same time those portions of the opposite ends of the blank between the slits 5 and the weather edge are turned under to 85 form the reinforcing flanges 6a. This operation divides the blank shown in the drawings longitudinally into four equal shingle elements, designated 7, 7a, 7b, 7c although it will be understood that if the blank were 90 longer, a larger number of shingle elements might be provided or if the blank were shorter a lesser number of elements would result.

The blank from which the shingles are 100 made may be of any suitable material but satisfactory results may be obtained when composition roofing is employed and if the manipulation of the shingle, that is to say, the bending of the flanges 6 and 6a is accomplished while the material is warm or hot, it is found that when the material cools, the parts will remain in the condition in which they were initially placed. I thus find it entirely practical to bend back the 105 flanges 6 and 6a as shown while the material is hot and then permit it to cool, leaving 110

ing the parts permanently in the relationship shown in Figure 2.

A number of strips such as shown in Figure 2 may be laid end to end to form a particular course on a roof and the next course thereupon laid, with the respective shingles end to end with the second mentioned course overlapping the shingles of the first course down to the line 8 in Figure 2 and the shingle elements of the second course staggered with relation to one another. When so laid, the turned under portion or flanges 6 and 6^a will cause the respective shingle elements between the line 8 and the weather edge to stand out substantially twice the thickness of the material of the blank so that the shingles will appear in bold relief in the finished shingle.

Instead of making a strip shingle in the manner described, the blank 1 may be made much longer than is shown in the drawings and may be sold by the running yard or by cutting the strip shown in Figure 2 transversely on the lines 9, a number of individual shingles may be produced and these individual shingles may be applied as individuals so that the invention is not restricted to the strip shingle of four elements as shown in the drawings.

I am further aware that instead of folding the marginal portions of the slots back upon themselves to form reentrant portions 10 with parallel edges, they may be folded back so that the reentrant portions will have diverging edges or partly parallel and partly diverging edges, so as to impart to the shingle elements tapering or semihexagonal configuration. The invention is not restricted in this respect since the invention is directed to the turning back of the marginal portions of slits extending transversely of the shingle and the particular bend is optional.

It will be apparent that the turned under portions 6 and 6^a not only serve as lifting or elevating portions to maintain the exposed parts of the respective shingle elements in upstanding position with respect to the elements of the subjacent course, but at the same time they serve to reinforce the edges of each reentrant portion 10, so that the curling of the points of the shingle

elements at the weather edge is precluded and also flapping of the shingles in the wind as frequently occurs with composition 55 roofing as now constructed is also obviated. The turned under portions therefore not only serve to expedite the manufacture and to impart to the shingle an aesthetic appearance, but at the same time they have 60 very important mechanical functions.

In Figure 3 I have shown a modified form of construction of which the present invention is susceptible. In this construction, slots 2^a extend perpendicular to the weather 65 edge of the strip to terminal slots 4^a extending longitudinally of the strip. Each terminal slot is disposed wholly upon one side of the associated slot 2^a so that only one side of the slot 2^a is turned under as shown at 70 6' to form the reinforcing and lifting flange and simultaneously form the reentrant portion 10^a.

Of the two constructions illustrated, however, I recommend the construction of Figures 1 and 2 as preferable since the shingle 75 is better structurally and looks better on a roof.

Aside from the shingle, the present invention also consists in the method of manufacturing the shingle.

Having thus fully described the invention, what I claim as new and desire to secure by Letters Patent is:

A shingle strip provided along one of its longitudinal edges with slits extending transversely into the strip and terminating short of the opposite longitudinal edge of the strip in relatively short longitudinal slits extending laterally from each transverse slit, and the marginal edges of each transverse slit being folded under the portions of the strip between adjacent transverse slits to lie beneath the plane of the body of the strip whereby the strip is provided along one of its longitudinal edges with shingle projections of increased thickness along their lateral edges, the folded under portions of the strip being concealed by the shingle projections when the shingle 100 is in place on a roof.

In testimony whereof I have signed the foregoing specification.

HARRY H. HONIGBAUM.
